ABSTRACT: A method of forming a subterranean cavity communicated with the surface through a drilled hole which includes the steps of drilling a hole from the surface of the ground to the subterranean situs at which the cavity is to be located, suspending an explosive at the lower end of the hole on a flexible suspending member extended downwardly in the hole from the surface, packing the hole around the suspending member with a stemming material, detonating the explosive, and then drilling out the stemming material in the hole to communicate the cavity formed by the explosion with the surface.

SUBTERRANEAN DRILLING METHOD

BACKGROUND OF THE INVENTION

The invention described herein was made in the course of, or under, an agreement with the U.S. Department of the Interior.

1. Field of the Invention

This invention relates to earth excavation for the purpose of geological exploration and/or oil and gas production. In a more specific, though nonlimiting, aspect, the invention relates to drilling methods useful in conjunction with nuclear energy utilization in oil and gas production.

2. Brief Description of the Prior Art

Nuclear explosives have been proposed for use in stimulating production of oil and gas from subterranean formations. By implanting nuclear devices in tight, thick formations and detonating the devices, the broken rock resulting from the explosion becomes the new well bore, and it has been conservatively estimated that a production rate of at least six times that of a conventionally completed oil or gas well can be realized from such procedure.

In the work which has been carried out previously in the field of nuclear fracturing of subterranean formations, the common practice has been to drill an explosive emplacement hole from the surface to the location in the formation to be fractured at which the nuclear device will be located at the time of detonation. The device with an attached firing cable is then lowered to the detonation situs on a suspension cable extended downwardly in the emplacement hole. A stemming material is then packed around the cables in the emplacement hole preparatory to detonating the nuclear device. After the nuclear device has been detonated to fracture the formation, a reentry hole or well is drilled from the surface to the cavity formed by the explosion, and the hydrocarbons are produced from such reentry well.

It will be apparent that the drilling of the described reentry well bore constitutes a further expense over that which would characterize this method of production were it possible to use the device emplacement hole for production. The drilling of the reentry hole also extends the time required to bring the production on stream. Drilling out the stemming material to clear the emplacement hole for production usage would be a relatively quickly and inexpensively performed operation as compared to the preparation of an entirely new reentry hole, but has not been possible due to the interference which the suspension and firing cables afford to drilling. Thus, in carrying out the drilling in conventional fashion using a rotary bit, the cables would quickly wrap around and foul the bit. Moreover, the cables would likely be damaged beyond further usage.

BRIEF DESCRIPTION OF THE PRESENT INVENTION

The present invention provides a method for forming a subterranean cavity communicated with the surface to facilitate production of fluids from the zone around the cavity, or study of the physical and geologic characteristics of the cavity, the material in the cavity and the earthen zone around the cavity, if such study is an objective. The method specifically permits nuclear fracturing of a subterranean formation followed by communication of the fractured zone with the surface through the drilling of but one hole from the surface to the formation.

Broadly described, the method of the invention comprises the steps of initially drilling a hole from the surface to the subterranean situs to be fractured, suspending at the situs to be fractured, an explosive connected to the lower end portion of a flexible member extended down the hole from the surface, closing the hole around the flexible member with a stemming material, detonating the explosive, and finally, removing sufficient stemming material from the hole to provide access to the fractured situs. The removal of the stemming material is carried out with the flexible member in place, and is preferably accomplished with a drill bit which oscillates, rather than rotates, and is therefore not fouled by the flexible member.

An object of the invention is to reduce the cost of producing oil and gas by nuclear stimulation of subterranean formations.

An additional object of the invention is to reduce the time required to produce oil and gas from underground cavities produced by a nuclear explosion.

A further and more specific object is to provide an improved method for drilling a hole to the situs of an underground nuclear explosion.

Additional objects and advantages of the invention will become apparent as the following detailed description of the invention is read in conjunction with the accompanying drawings.

BRIEF DESCRIPTION OF THE DRAWINGS

FIG. 1 is a schematic illustration of a nuclear device positioned in a subterranean formation by suspending the device on a cable extended to the surface through an emplacement hole.

FIG. 2 is a sectional view taken along line 2—2.

FIG. 3 is a schematic illustration of the earthen environment illustrated in FIG. 1 as it appears after detonation of the nuclear device.

FIG. 4 is a perspective view, with parts broken away for clarity of illustration, showing one type of apparatus used for drilling out the emplacement hole following the detonation of the nuclear device.

FIG. 5 is an enlarged sectional view taken along line 5—5 of FIG. 4 and showing one type of drill bit useful for drilling out the emplacement hole, and showing the orientation of the bit with respect to the suspension cable during drilling.

DETAILED DESCRIPTION OF A PREFERRED EMBODIMENT OF THE INVENTION

Referring initially to FIG. 1, a nuclear device 10 susceptible to detonation to produce an explosion is positioned in the earth 12 at a location within a hydrocarbon bearing formation. The device 10 is connected to the lower end of a cable 14, or other flexible suspending member. The cable 14 extends to the surface through an emplacement hole 16, and has a firing cable 18 passing through the interior thereof for detonating the nuclear device. The emplacement hole 16 can be drilled by any suitable method, such as those conventionally employed in the production of oil and gas, and will be comparable in depth to the bore holes drilled for that purpose. In the use of nuclear devices for nuclear stimulation of production, however, emplacement holes must be larger in diameter to some degree than conventional bore holes drilled to produce oil and gas due to the size of the nuclear devices presently used.

The emplacement hole 16 is cased by a suitable casing 20 over a major portion of its length. After the nuclear device 10 has been lowered to the desired position, the hole around the cable 14 is packed with a stemming material 21, such as gravel. The stemming material 21 is preferably a relatively soft material which can be relatively easily removed by drilling following the detonation of the nuclear device 10. The cable 14 may be clamped at the surface by a suitable clamp 22, or such clamping may be deferred until a later time in the procedure as hereinafter explained.

When the packing of the stemming material 21 around the cable 14 is completed, the nuclear device 10 is detonated from the surface by passing an electrical current through the firing cable 18. The explosion of the nuclear device 10 initially creates a fireball having a temperature of several million degrees. The fireball expands, forming a cavity which ultimately becomes sufficiently large that the roof will not support itself and falls in, filling the cavity with rubble. The appearance of a cavity 24 and the rubble 26 which has fallen into the cavity are depicted in FIG. 3. Radial fractures 28 extend outwardly from the cavity 24 for a distance equivalent to three or four times the radius of the cavity, and a striking potential production rate of hydrocarbons from the adjacent formation is attained.

To produce hydrocarbons from the situs stimulated by the nuclear explosion, a production well must be formed to convey the hydrocarbons to the surface. In accordance with the present invention, the stemming material 21 is drilled out of the emplacement hole 16 to provide communication between the cavity 24 and the surface of the ground. One type of apparatus which can be used for drilling out the stemming material 21 is depicted in FIGS. 4 and 5.

A drilling rig is designated generally by reference numeral 30. On the rig floor 32 a modified rotary table 34 is secured in conventional fashion. The rotary table 34 includes the usual internal ring gear and pinion (not visible) for rotating the kelly drive 36. The rotary table has been modified, however, to permit the ring gear to be oscillated about its rotational axis, rather than being constantly rotated in one direction, as is the practice in conventional drilling. The structural modifications used to provide oscillation include a gear 38 secured to the projecting end of the drive shaft 40 which drives the ring gear of the rotary, and a rack 42 engaging the gear 38 and secured to one end of a piston rod 44. The piston rod 44 is connected to, and movable with, a piston (not visible) located in a cylinder 46 and subjected to alternately acting forces which reciprocate the piston within the cylinder. The force for reciprocating the piston may be developed by steam, hydraulics, internal combustion, pneumatics or any of the other methods known to the art and calculated to provide sufficient power to oscillate the drill stem as hereinafter described.

As the kelly drive 36 is oscillated by the oscillating ring gear of the rotary table, the kelly 48 in the drill stem is also oscillated and the entire drill stem from kelly to bit undergoes such oscillating movement. It will be noted in referring to FIG. 4 that the cable 14 is guided along one side of the drill string by guide brackets 50 disposed at longitudinally spaced intervals on the string. The cable 14 can slide through the guide brackets 50 as the bit descends in the emplacement hole 16, and the retention of the cable alongside the drill string in this manner prevents it from whipping during oscillation of the drill stem, and protects it from contact with the casing 20. Near the lower end of the drill string, the cable 14 is extended through a slot 52 in a tubing section 54, and passes through the central bore in the tubing out of the central mud passageway in the drill bit 56. The passageway may be enlarged if necessary to accommodate both the cable 14 and the mud flow required for drilling.

At the commencement of the drilling operation, the cable 14 is disconnected at the surface and extended upwardly through the central mud passageway in the bit 56, through the lower tubing section 54, and through the slot 52. It is then reconnected or simply clamped in any suitable manner to the top of the casing 20 and the drilling is commenced. As the drill string is extended downwardly in the emplacement hole 16, the cable 14 is pressed into the successive guide brackets 50 on the string. It may be pointed out that, as an alternative to the described cable threading procedure, the bit 56 and lower tubing section 54 can be constructed as segmented structures each having two segments hinged together, and openable relative to each other to permit the cable to be inserted as described.

The bit 56 has three teeth 56a, 56b and 56c symmetrically disposed about the oscillational axis of the string, and each having a toe portion which is tapered to provide a cutting edge which bites into the stemming material 21 when the bit oscillates in one direction, and to ride back over the stemming material without cutting when the bit oscillates in the opposite direction. Because of this action, the alternating torsional forces across the drill stem couplings will be unbalanced with a resulting tendency of such couplings to be tightened. If desired, however, the joints of drill pipe may be pinned to each other with removable pins to form a mechanically positive lock against unthreading due to the oscillating movement.

As the bit 56 bears against the bottom of the hole it is drilling, it oscillates about the cable 14. Frictional wear on the cable at the location where it passes along the axis of the drill stem is reduced by the lubricating action of the drilling mud

which is circulated down the drill pipe. Also sharp and abrasive cuttings are pushed away from the cable 14 by the outflowing mud as it leaves the lower end of the bit. The mud is circulated upwardly to the surface through the annulus between the casing 20 and drill string in conventional fashion.

Although the method of drilling proposed by the present invention does subject to a twisting action the suspension and firing cables required for the emplacement and detonation of the nuclear device, oscillation of the drill stem is controlled to reduce the oscillatory amplitude to a level at which the cables are not unduly stressed or damaged. As the depth at which the bit is located is increased, the length of free cable is correspondingly increased, and the amplitude of the oscillations can be increased or varied to increase the effectiveness of the cutting action developed by the bit 56.

The disclosure heretofore has been based on the assumption that cable 14 will, after stemming, be located approximately along the central axis of emplacement hole 16. Under these circumstances, a procedure wherein the cable is passed into the central portion of the bit will be most feasible. It is quite possible, however, that under some circumstances emplacement hole 16 will have deviated from the vertical. Should this occur, cable 14 would not be expected to lie along the central axis of the emplacement hole, but would rather be in contact with a side of the hole. In this event, an alternative drilling procedure may be adapted wherein a drill bit smaller than the internal diameter of casing 20 is used to remove stemming material 21. In this procedure, the bit will be positioned off-center in casing 20 in a direction away from cable 14. Moreover, the size of the bit will be chosen so that there will be sufficient clearance between the bit and the side of casing 20 at which cable 14 is located to allow free oscillation of the bit without entanglement of the cable. The upward end of cable 14 would, of course, be clamped at or near the wellhead.

Specific embodiments of the present invention have been described to illustrate how the invention may be practiced by adherence to certain basic principles. These same principles may be utilized, however, to achieve the objects of the invention when certain undisclosed variations in, and departures from, the precise steps and structures herein described are employed. Practices which involve such variations and departures which are yet encompassed by the basic principles underlying the invention are therefore deemed to be within the spirit and scope of the invention except as the same may be necessarily limited by the accompanying claims or reasonable equivalents thereof.

What is claimed is:

1. The method of forming a subterranean cavity communicated with the surface through a drilled hole comprising: drilling a hole from the surface of the ground to the subterranean situs at which the cavity is to be located; suspending an explosive in the hole on a flexible suspending member extended downwardly in the hole from the surface; packing the hole around the suspending member with a stemming material; detonating the explosive; drilling out the stemming material in the hole to communicate the cavity formed by the explosion with the surface; and

stationarily holding a point on the suspending member at the surface during the drilling out of the stemming material to prevent the suspending member from descending in the hole.

2. The method of forming a subterranean cavity communicated with the surface through a drilled hole comprising: drilling a hole from the surface of the ground to the subterranean situs at which the cavity is to be located; suspending an explosive in the hole on a flexible suspending member extended downwardly in the hole from the surface; packing the hole around the suspending member with a stemming material; detonating the explosive; and

drilling out the stemming material in the hole by oscillating a drilling bit against the bottom of the hole to communicate the cavity formed by the explosion with the surface.

3. The method of forming a subterranean cavity communicated with the surface through a drilled hole comprising: 5
 drilling a hole from the surface of the ground to the subterranean situs at which the cavity is to be located; suspending an explosive in the hole on a flexible suspending member extended downwardly in the hole from the surface; 10
 packing the hole around the suspending member with a stemming material; detonating the explosive; and
 drilling out the stemming material in the hole to communicate the cavity formed by the explosion with the surface, wherein drilling out of the stemming material is accomplished by oscillating a drilling bit in an arcuate path with the flexible suspending member located at the center 15

20

of oscillation.

4. The method of forming a subterranean cavity communicated with the surface through a drilled hole comprising: 5
 drilling a hole from the surface of the ground to the subterranean situs at which the cavity is to be located; suspending an explosive in the hole on a flexible suspending member extended downwardly in the hole from the surface; 10
 packing the hole around the suspending member with a stemming material; detonating the explosive; and
 drilling out the stemming material in the hole to communicate the cavity formed by the explosion with the surface, wherein drilling out of the stemming material is accomplished by oscillating a drilling bit in an arcuate path with the flexible suspending member located adjacent to and outside the path of oscillation.

UNITED STATES PATENT OFFICE
CERTIFICATE OF CORRECTION

Patent No. 3623555 Dated November 30, 1971

Inventor(s) Carroll F. Knutson and Bruce G. Bray

It is certified that error appears in the above-identified patent and that said Letters Patent are hereby corrected as shown below:

In line 5 of Column 1 of the above-referenced Patent, the phrase "U. S. Atomic Energy Commission and the" was omitted in the printing of the Patent by the Patent Office. Lines 4, 5, and 6 of Column 1 should read:

The invention described herein was made in the course of, or under, an agreement with the U. S. Atomic Energy Commission and the U. S. Department of the Interior.

Signed and sealed this 9th day of May 1972.
